UNITED STATES PATENT OFFICE.

GEORGE A. ROBERTSHAW, OF GREENSBURG, PENNSYLVANIA.

FUEL-CONTROL SYSTEM.

Application filed January 29, 1926. Serial No. 84,745.

The present invention relates broadly to an improved system or apparatus for governing the flow of fuel to a burner, and more particularly to a system employing a novel arrangement of diaphragm valves for controlling the passage of gas.

At the present time diaphragm valves are being used to a considerable extent in connection with the control of gas to a burner. 10 In spite of the rapidity with which it has heretofore been possible to operate such valves whereby a true snap action has been attempted, the valves have met with the objection that they do not constitute a means 15 of control of the true snap action type which is effective either for permitting a full flow of the gas or cutting off such flow entirely. This objection has become more and more serious as the burner art has developed, due 20 to the tendency in manufacturing burners to increase the heating capacity thereof without increasing their size, this usually being done by increasing the size of the holes in the burners. This makes the burners liable to 25 flash back, so that it is extremely important to so control the supply of fuel to the burner that when operative it will burn only at its greatest consuming point, and when the desired heating has been accomplished the supply 30 of gas will be completely and instantly shut off.

With a diaphragm valve, when the diaphragm becomes almost balanced, that is, when the pressure on the top and bottom of 35 the diaphragm becomes nearly equal, there is at times a slight leakage of gas through the seat. This prevents free use of such valves, as it has been necessary to select burners for use therewith that will not readily 40 flash back.

In accordance with the present invention, there is provided a construction making it possible to utilize a thermostatically controlled diaphragm valve as a true snap-action valve by delaying the unrestricted passage of gas from such valve to the burner.

In the accompanying drawings there is shown, for purposes of illustration only, one preferred embodiment of the present invention, it being understood that these drawings do not define the limits of my invention, as 50 changes in the construction and operation disclosed therein may be made without departing either from the spirit of the invention or the scope of my broader claims.

In the drawings:

Figure 1 is a diagrammatic side elevational view, partly broken away and partly in section, illustrating one embodiment of the invention; and

Figure 2 is a detail sectional view on the line II-II of Figure 1, looking in the direction of the arrows.

The invention is illustrated as utilized in connection with a hot water heating system, but it will be understood that this use is illustrative only of one of the many uses to which the invention may be placed.

In the drawings, there is shown a hot water reservoir 2 having a cold water inlet 3 and a hot water outlet 4. The water is adapted to be heated by a heater 5 cooperating with the hot water circulating pipe 6, as is customary in the art, the heater having any desired form of burner 7.

Extending into the reservoir 2 is a portion of the thermostat for the thermostatic valve 8. This valve may be of any desired construction, but is preferably of the general construction illustrated in my Patent No. 1,107,549, dated August 18, 1914, adapted to open as the temperature of the water in the reservoir increases. This valve is adapted to control the flow of gas, or other fuel, from a main supply pipe 9 to the chamber 10 above the diaphragm 11 in the casing 12. With the main supply valve 13 and the auxiliary valve 14 open, the gas is free to flow from the supply pipe to the inlet of the valve 8. If this valve is open, the gas will pass through the pipe 15 to the chamber 10 as described. This will build up an operating pressure above the diaphragm 11, tending to maintain the valve disk 16 carried thereby in contact with the seat 17 to prevent the flow of gas from the inlet 19 to the outlet 18. As the temperature of the water in the reservoir 2 decreases, the valve 8 will be closed to cut off the flow of gas to the chamber 10, and thereby permit the diaphragm 11 to raise to

100 permit the flow of gas to the outlet 18. Normally, this outlet is directly connected to the burner 7 for feeding fuel thereto. It will be apparent, however, that at certain times during the operation of the diaphragm, as 105 when the effective pressure above the diaphragm becomes nearly equal to the effective pressure below it, and the valve disk 16 is attempting to close communication between the inlet and outlet, there is a tendency 110

for a slight amount of gas to leak by the seat 17 to the burner. This condition obtains when the thermostat operates to open valve 8, due to an increase of temperature in 5 the part being controlled above that desired, whereby gas pressure is transmitted from pipe 9 to the upper side of the diaphragm 11, or at a time when the temperature of the water in the reservoir has dropped below 10 that desired and the thermostat is just closing the valve 8 and thereby gradually reducing the pressure above the diaphragm 11. In other words, this operation is apt to occur just before an increase in gas supply from 15 a condition in which only the pilot has been operating and also at a time when a full supply of gas is being cut off from the burner 7, the periods corresponding respectively when there is a flash back in the ordinary burner. With certain types of burners this operation is dangerous, as it tends to produce an objectionable flash back.

By the present invention this operation in accordance with the usual practice is 25 made impossible, and a true snap action operation is secured. This is accomplished by connecting the outlet 18 to the inlet 20 of a second casing 21 having its outlet 22 connected to the burner 7. This casing is provided with a similar diaphragm 23 carrying 30 a valve 24 cooperating with the seat 25. This second casing is provided with a small air relief opening 0 above the diaphragm to permit free movement of the diaphragm.

35 For the purpose of illustrating the operation of the present system, it may be assumed that the diaphragms are not adapted to lift until there is a pressure underneath them of substantially one-half inch of water, 40 and that the effective pressures above and below the diaphragm 11 are so nearly balanced that there is a small leakage to the outlet 18. This leakage would not pass the valve 24, but would be delayed thereby and 45 gradually build up a pressure in the inlet 20. By the time a pressure corresponding to one-half inch of water column has accumulated under the diaphragm 23, there is a corresponding back pressure on the valve 16. 50 This back pressure causes the diaphragm 11 to lift rapidly and in turn supply a full head of gas to the under side of the diaphragm 23. This instantly raises the diaphragm 23, giving a full flow of gas to the 55 burner.

The operation before referred to occurs by reason of the differential areas of the diaphragms subjected to pressure built up by the leakage of gas. In accordance with 60 the embodiment illustrated, the central portion of the diaphragm which cooperates with the inlet has a smaller area than the annulus which is in communication with the outlet. It will be noted that the connection 65 between the valve casings communicates

with the outlet of the first valve and the inlet of the second valve. Therefore, a given accumulated pressure in this connection when great enough to lift the diaphragm 11 will not be enough to lift the diaphragm 70 23. This insures complete opening of the diaphragm 11 before the diaphragm 23 moves at all, and this complete opening then subjects the diaphragm 23 to a full head. During the closing operation, the minute the 75 diaphragm 11 moves to closed position to thereby relieve the diaphragm 23 of the full pressure, the diaphragm 23 closes quickly due to the construction of the diaphragm, as well as the force of gravity. It will thus be 80 seen that a true snap action is obtained.

The reverse operation is also true. When the burner has operated for a sufficient length of time to raise the temperature of the water in the reservoir 2 to a point at 85 which the valve 8 is opened, a gradually increasing pressure is built up in the chamber 10. When this pressure exerts an effective load on the diaphragm nearly equal to the effective load exerted upwardly on the diaphragm by the gas in the inlet 19 so that the valve 16 becomes nearly balanced, the flow of gas to the inlet 20 of the second diaphragm valve will be restricted to a point that will not give the necessary pressure for 90 holding the diaphragm 23 raised. It will therefore instantly lower, causing the valve 24 to engage its seat 25 and quickly cut off the flow of gas to the burner. It will thus be seen that a substantially true snap action 100 valve is provided.

If it is desired to provide a continuous pilot, suitable connection may be made with the pipe 26 through a valve 27. In order to conserve any gas within the chamber 10, a 105 second pilot 28 may be provided connected to the pipe 15 through the controlling valve 29. It will be apparent that this second pilot will always have a full flow of gas when the flow to the main burner 7 is cut off, and will 110 be put out of operation automatically when a gas flow is established to the burner 7. While it may be effectively used for lighting the burner, it is sometimes desirable to provide a continuous burning pilot as before set 115 forth.

This application is a continuation in part of my earlier application Serial No. 727,709, filed July 23, 1924.

The advantages of the present invention 120 arise from the provision of a system in which a pressure operated valve, and preferably of the diaphragm type, is operated as a true snap action valve.

I claim:

1. In a fuel control, a burner, a diaphragm valve controlling the flow of fuel to the burner, and a second diaphragm valve for delaying the unrestricted passage of fuel from the first mentioned diaphragm 130

- valve to the burner, said valves being connected in series and adapted to be both open while the burner is in operation, substantially as described.
5. 2. In a fuel control, a burner, a diaphragm valve controlling the flow of fuel to the burner, and means for initially delaying the unrestricted passage of fuel from said valve to the burner and thereafter permitting unrestricted passage of such fuel, substantially as described.
10. 3. In a fuel control, a burner, a supply line, a pressure operated valve controlling the flow of fuel through said line to the burner, and a second pressure operated valve in said line for delaying the unrestricted passage of fuel from said first mentioned valve to the chamber, said valves during operation of the burner being open con-20 comitantly, substantially as described.
15. 4. In a fuel control, a burner, a valve operated in accordance with pressure differences on opposite sides thereof, and means for causing the leakage of gas which takes 25 place past said valve to build up an operating pressure effective for quickly moving said valve to full open position, substantially as described.
20. 5. In a fuel control, a burner, a valve operated in accordance with pressure differences on opposite sides thereof, and means for causing the leakage of gas which takes 30 place past said valve to build up an operating pressure effective for quickly moving said valve to full open position, said means comprising a second valve in series with the first mentioned valve, substantially as described.
35. 6. In a fuel control, a burner, a diaphragm valve having a fuel inlet and outlet, and a second diaphragm valve communicating with the outlet of the first mentioned diaphragm valve for collecting gas leaking past said valve and building up 40 an operating pressure against the outlet side thereof, substantially as described.
45. 7. In a fuel control, a burner, a diaphragm valve having a fuel inlet and out-
- let, and a second diaphragm valve communicating with the outlet of the first mentioned 50 diaphragm valve for collecting gas leaking past said valve and building up an operating pressure against the outlet side thereof, both of said valves being adapted to be open under predetermined pressure conditions, 55 substantially as described.
8. In a pressure system, a burner, and a plurality of diaphragm valves in series with said burner, one of said valves cooperating with the outlet of the other of said valves 60 to build up an operating pressure against the outlet side thereof, substantially as described.
9. In a burner system, a burner, a diaphragm valve controlling the flow of fuel to 65 said burner, said valve having an inlet and an outlet, and a pressure operated release means cooperating with the outlet of said valve to collect gas leaking thereby for building up a predetermined operating pres-70 sure against the outlet side thereof, substantially as described.
10. In a fuel control system, a burner supply line, a burner supplied thereby, a plurality of diaphragm valves connected in 75 series in said line and in advance of said burner, and means cooperating with one of said valves for varying the pressure effective against one side thereof, said valves both being adapted to occupy open position 80 during periods of operation determined by the operation of said means to thereby permit an unrestricted flow through said supply line, substantially as described.
11. In a fuel control system, a burner 85 supply line, a plurality of diaphragm valves connected in series in said line, and a temperature responsive control for the first of said valves in series, the second of said valves being controlled by the pressure fluid 90 passing the first valve, substantially as described.

In testimony whereof I have hereunto set my hand.

GEORGE A. ROBERTSHAW.
